UNITED STATES PATENT OFFICE.

JOHN A. BOEHRINGER, OF SPRINGFIELD, NEW YORK, ASSIGNOR TO STAR CHANDELIER CO., INC., OF NEW YORK, N. Y., A CORPORATION OF NEW YORK.

DESIGN FOR A CEILING PLATE FOR LIGHTING FIXTURES.

Application filed March 17, 1927. Serial No. 21,163. Term of patent 3½ years.

To all whom it may concern:

Be it known that I, JOHN A. BOEHRINGER, a citizen of the United States, residing at 145-85 Aberdeen Street, Springfield, Long Island, in the county of Queens and State of New York, have invented a new, original, and ornamental Design for a Ceiling Plate for Lighting Fixtures, of which the following is a specification, reference being had to the accompanying drawing, forming part thereof.

Figure 1 is a plan view of the ceiling plate, only one third being shown in detail, the other two thirds being each an exact duplicate of the third shown in detail.

Figure 2 is a section on line 2—2 of Figure 1, showing my new design.

I claim:

The ornamental design for a ceiling plate for lighting fixtures, as shown.

JOHN A. BOEHRINGER.
